[57] CLAIM

The ornamental design for a bowling ball carrying case, substantially as shown and described.

DESCRIPTION

FIG. 1 is a perspective view of a bowling ball carrying case showing my new design;
FIG. 2 is a front elevational view thereof;
FIG. 3 is a right side elevational view thereof;
FIG. 4 is a left side elevational view thereof;
FIG. 5 is a top plan view thereof;
FIG. 6 is a rear elevational view thereof;
FIG. 7 is a bottom plan view thereof; and
FIG. 8 is a perspective view of the bowling ball carrying case in the opened position.

*Fig. 1.**Fig. 2.**Fig. 3.**Fig. 4.**Fig. 5.**Fig. 7.**Fig. 6.**Fig. 8.*
